NEUTRALIZATION CIRCUIT FOR SHORT
WAVE TRANSMITTERS

Werner Buschbeck, Berlin, Germany, assignor to
Telefunken Gesellschaft für Drahtlose Tele-
graphie m. b. H., Berlin, Germany, a corporation
of Germany

Application February 2, 1938, Serial No. 188,233
In Germany March 5, 1937

9 Claims. (Cl. 179—171)

The invention relates to a neutralizing circuit for short waves in which essential drawbacks of the hitherto known circuits are overcome.

In order to more readily understand the invention, a discussion will first be given with respect to known circuit arrangements and their difficulties.

Figs. 5 and 6 represent two well known neutralizing circuit arrangements of the prior art.

- 10 In Fig. 5 a balance may be readily achieved between tube capacity C_{ag} and neutralizing capacity C_n , such that a voltage introduced in the input does not result in developing a voltage across the output. However, in this condition of adjustment, voltage across the output circuit sets up a potential difference between grid and cathode by way of the voltage dividing capacity path C_{ag} , C_1 . This is not neutralized by any feed back through the neutralizing condenser C_n because the balance before mentioned assures that no current flows in the input coil system as a result of voltage across the output circuit, and therefore there is no way for current through the neutralizing condenser to influence the potential difference between grid and cathode. Thus, in spite of the bridge arrangement being theoretically perfect for preventing output voltage from reacting upon the input circuit, it nevertheless does not prevent output voltage from being fed back in degenerative phase to the input electrodes, that is, between grid and cathode. Fig. 5 is sometimes rearranged so that the cathode of the amplifier is connected to the center of the input coil system rather than to the center 35 of the capacity branch thereacross. In this case the same phenomenon occurs except that the amount of voltage fed back is reduced in proportion to the coefficient of coupling between the two halves of the input coil, and the phase of the 40 feed back becomes regenerative due to the reversal of the sign of the reactance between grid and cathode.

In Fig. 6 a similar known neutralizing arrangement demonstrates that while a perfect bridge balance will prevent any coupling between the input and output circuits, except by virtue of the desired relay action of the tube, the voltage impressed upon the input circuit will produce a voltage between anode and cathode and vice versa. This again is true whether the cathode be connected to an intermediate point on the capacitive branch of the output circuit or to a corresponding intermediate point on the inductive branch thereof.

55 Thus, it is evident that in the arrangements of

the known art a bridge balancing achieves only one of two desirable results. It is the object of the present invention to attain both the complete decoupling of input and output circuits other than through the electron relaying action of the tube and also to prevent voltage in the output circuit from causing any potential difference between the tube input electrodes. This is done by employing an auxiliary, symmetrically arranged network, arranged to provide a resonant short circuit path at the operating frequency between the cathode and the cold electrode which is connected to the divided circuit of the amplifier. This auxiliary circuit may, however, in practice be coalesced with the already existing divided circuit.

The invention will now be described in greater detail in connection with the accompanying drawings, wherein:

Figs. 1 and 2 illustrate two ways of eliminating feed-back in the grid neutralizing circuit in accordance with the invention, and

Figs. 3 and 4 illustrate two ways of eliminating feed-back in the anode neutralizing circuit in accordance with the invention.

Figs. 5 and 6 represent well known circuit arrangements shown for the purpose of the above exposition.

Fig. 1 shows a grid neutralizing circuit comprising the tube R, the grid-anode capacity C_{ag} , the neutralizing capacity C_n and the capacities C_1 and C_2 of the oscillatory circuit. Item G represents the grid point, K is the cathode point, while A designates the anode point and N the neutral point. The oscillatory input circuit lies between N and G. In accordance with the invention a T element is placed in parallel to this circuit, said T member consisting of the two inductances L and a capacity C. The inductances L may serve at the same time as the coil of the oscillatory circuit. Without the condenser C a reactive coupling potential would exist at the grid point G which is determined by the proportion of the capacities C_{ag} and C_1 . This reactive coupling could, of course, be reduced at will by increasing the value of C_1 , but this is not feasible in case of short waves, and ultra short waves. If the capacity C is inserted and tuned in such a manner that the parallel connection of the two coil halves through which the currents arriving via C_n and C_{ag} pass in opposite directions, in other words the value

$$\frac{L-M}{2}$$

(wherein M is the mutual inductance between the two halves) is in resonance with C , a short circuit will be formed between G and K and between N and K as viewed from the plate cathode circuit. In other words, the feed back will be reduced to zero. The T element may consist either of two inductances and one capacity, as shown in Fig. 1, or it may consist of two capacities and one inductance, according to Fig. 2. In applying 10 the invention, it is wholly immaterial whether the voltage division in the neutralizing bridge proper is capacitive or inductive.

In like manner, the passing of energy from the control transmitter to the main transmitter 15 can be eliminated in the anode neutralizing circuit while the circuit need not be further developed into a push-pull double bridge as was hitherto the case. The T element lies, as shown in Fig. 3, between the points A , N , and K . In Fig. 20 3 there is represented for the sake of clearness the bridge arrangement for the entire circuit, whereby R is again the tube, C_1 and C_2 the voltage divider capacities and A , N , K the anode point, neutral point and cathode point respectively. 25 Between K and G the control transmitter is inserted and between A and N the main transmitter. At the proper tuning of the T element, the anode-cathode path is short circuited as viewed from the control transmitter. Fig. 4 shows another 30 mode of embodiment of Fig. 3 which corresponds to Fig. 1. It should, moreover, be emphasized that the effectiveness of the arrangement described is not limited to rigorously exact series resonance tuning of the T element and that any- 35 where in the proximity of resonance an essential improvement over the hitherto known circuits is obtained. The resultant impedance X of a series element having the resonance resistance X_0 increases at first gradually as the actual frequency 40 w departs from the resonant frequency w_0 , in accordance with the equation

$$X = X_0(w/w_0 - w_0/w)$$

For obtaining substantially all the results of the 45 invention, it is only necessary that this value remain lower than the reactance X_{AG} of the grid-anode capacity.

The conditions are not quite as simple if the cathode, or anode, or both electrodes are not 50 directly accessible, which in the case of ultra short waves is mostly the case owing to the electrode lead-ins. In this case, at anode neutralization, the resistance value of the T member, as viewed from the side of the control transmitter, 55 must no longer be zero, but it must be so apportioned that the voltage produced directly at the anode-cathode path by the exciting alternating voltage disappears. The determination of the required resistance of the T element, by way of 60 calculation, depends on the type of the circuit and after all on the type of the tube employed. An especially simple calculation is possible in case of tubes having a concentric grid and cathode and twin cathode structure, since hereby a bridge 65 relationship can be deduced in which the anode-cathode path lies in a diagonal of the bridge containing the inductances of the electrode lead-ins. The actual calculation will not be carried through herein, since it does not modify the general principle of the invention. It may be said that there 70 lies a greater advantage in carrying out the correct tuning of the T member through experimentation.

The invention can be applied in almost all 75 bridge neutralizing circuits in which, at exact

balance, a counter coupling or feed back occurs between an input or output circuit and a pair of tube electrodes.

What is claimed is:

1. The combination with a high frequency system having an input and an output circuit, and an electron discharge device having a grid and a cathode connected across a portion of the input circuit, and an anode and said cathode connected to said output circuit, said system having means for preventing voltage across said output circuit from producing a potential difference between the terminals of said input circuit, of a reactance in the connection between said cathode and said input circuit, said reactance being of opposite sign to the reactance of that portion of the input circuit to which it is connected and having a magnitude such that voltage across said output circuit produces a voltage drop across said reactance equal and opposite to the voltage across said portion of said input circuit at the operating frequency, whereby voltage across said output circuit produces neither any potential difference across said input circuit nor any appreciable potential difference between grid and cathode. 25

2. The combination with a high-frequency system having an input and an output circuit, and an electron discharge device having an anode and a cathode connected across a portion of the output circuit, and a grid and said cathode connected to said input circuit, said system having means for preventing voltage across said input circuit from producing a potential difference between the terminals of said output circuit, of a reactance in the connection between said cathode and said output circuit, said reactance being of opposite sign to the reactance of that portion of the output circuit to which it is connected and having a magnitude such that voltage across said input circuit produces a voltage drop across said reactance equal and opposite to the voltage across said portion of said output circuit at the operating frequency, whereby voltage across said input circuit produces neither any potential difference across said output circuit nor any appreciable potential difference between anode and cathode. 45

3. In an amplifier circuit having a vacuum tube having input and output electrodes, an output circuit connected to said output electrodes, and an input circuit for energizing said input electrodes, the method of eliminating feed-back of voltage from said output circuit to said input electrodes due to inherent interelectrode capacity, which includes as a first step neutralizing voltage across said input circuit due to voltage across said output circuit, and as a second step utilizing resonance effects to eliminate residual voltage between input electrodes due to potential difference existing across the portion of said input circuit to which said input electrodes are connected. 55

4. In an amplifier circuit having a vacuum tube having input and output electrodes, an output circuit connected to said output electrodes, and an input circuit for energizing said input electrodes, the method of eliminating feed-back of voltage from said output circuit to said input electrodes due to inherent interelectrode capacity, which includes as a first step neutralizing voltage across said input circuit due to voltage across said output circuit, and as a second step utilizing series resonance to eliminate residual voltage between input electrodes due to potential difference existing across the portion of said input circuit to which said input electrodes are connected. 70 75

5. The combination with an amplifier circuit having a vacuum tube having a cathode and a pair of cold electrodes and input and output circuits therefor, a bridge neutralizing circuit connected to said electrodes in such manner that a voltage introduced in the input circuit will not result in developing a voltage across the output, except by virtue of the desired relay action of the tube, said bridge neutralizing circuit including a 5 divided circuit to which the cathode and one of said cold electrodes are connected, of means providing a resonant short circuit path at the operating frequency between said cathode and said one cold electrode.
- 10 6. In an amplifier circuit having a vacuum tube having input and output electrodes, an output circuit connected to said output electrodes, and an input circuit for energizing said input electrodes, the method of eliminating transfer 10 of voltage from said input circuit to said output electrodes due to inherent interelectrode capacity, which includes as a first step neutralizing voltage across said input circuit due to voltage across said output circuit, and as a second step 15 utilizing resonance effects to eliminate residual voltage between output electrodes due to potential difference existing across the portion of said output circuit to which said output electrodes are connected.
- 20 7. In an amplifier circuit having a vacuum tube having input and output electrodes, an output circuit connected to said output electrodes, and an input circuit for energizing said input electrodes, the method of eliminating transfer of voltage from said input circuit to said output electrodes due to inherent interelectrode capacity, which includes as a first step neutralizing voltage across said input circuit due to voltage across said output circuit, and as a second step 25
- 25 30
- 30 35
- utilizing series resonance to eliminate residual voltage between output electrodes due to potential difference existing across the portion of said output circuit to which said output electrodes are connected. 5
8. In an amplifier circuit having a vacuum tube having first and second sets of electrodes, an output circuit connected to said second electrodes and an input circuit for energizing said first electrodes, the method of eliminating transfer of voltage from one of said circuits to that set of electrodes to which it is not directly connected due to inherent interelectrode capacity, which includes as a first step neutralizing voltage across said input circuit due to voltage across said output circuit, and as a second step utilizing resonance effects to eliminate residual voltage between the electrodes of said one set due to potential difference existing across the portion of the circuit to which said one set of electrodes 20 is connected. 15
9. In an amplifier circuit having a vacuum tube having first and second sets of electrodes, an output circuit connected to said second electrodes and an input circuit for energizing said first electrodes, the method of eliminating transfer of voltage from one of said circuits to that set of electrodes to which it is not directly connected due to inherent interelectrode capacity, which includes as a first step neutralizing voltage across said input circuit due to voltage across said output circuit, and as a second step utilizing series resonance to eliminate residual voltage between the electrodes of said one set due to potential difference existing across the portion of the circuit to which said one set of electrodes is connected. 30 35
